Patented Jan. 5, 1965

200,013

JUG

Arnold I. Lorenzen, deceased, late of Toledo, Ohio, by Gertrude M. Lorenzen, executrix, Toledo, Ohio, assignor to Owens-Illinois Glass Company, Toledo, Ohio, a corporation of Ohio

Filed Apr. 15, 1964, Ser. No. 79,517

Term of patent 14 years

(Cl. D58—5)

FIG. 1

The characteristic features of this design reside in that portion shown in full lines.

What is claimed is:

The ornamental design for a jug, substantially as shown and described.
